Primary Examiner — George D. Kirschbaum*Assistant Examiner* — Maria J Edwards(74) *Attorney, Agent, or Firm* — The Rapacke Law Group, P.A.; Andrew S. Rapacke(57) **CLAIM**

The ornamental design for a moveable barrier gate bracket, as shown and described.

DESCRIPTION

FIG. 1 is a perspective view of the moveable barrier gate bracket;

FIG. 2 is a front view thereof;

FIG. 3 is a rear view thereof;

FIG. 4 is a top view thereof; and,

FIG. 5 is a left side view thereof.

Please note the bottom view is a mirror image of the top view shown in FIG. 4 and the right side view is a mirror image of the left side view shown in FIG. 5. The broken lines in the drawings illustrate environmental subject matter and form no part of the claimed design.
